UNITED STATES PATENT OFFICE.

LEWIS J. BAZZONI, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

MACHINE FOR USE IN HANDLING BLANKS.

Application filed March 31, 1919. Serial No. 286,615.

To all whom it may concern:

Be it known that I, LEWIS J. BAZZONI, a citizen of the United States, residing at Swampscott, in the county of Essex and 5 State of Massachusetts, have invented certain Improvements in Machines for Use in Handling Blanks, of which the following description, in connection with the accompanying drawings, is a specification, like reference characters on the drawings indicating like parts in the several figures.

This invention relates to machines for use in handling blanks and is herein illustrated as embodied in a machine for use in handling uppers of shoes.

It is customary in some shoe factories to tie the uppers in bundles of a given number—commonly thirty-six—after they have been finished by the vamper preparatory to 20 taking them to the assembler. Hitherto the vamper has been accustomed to pile the finished blanks one by one beside her on the bench which supports her sewing machine as fast as she has finished them and then to tie 25 them in bundles of the required number. Inasmuch, however, as it is difficult for her to keep track at all times of the number of finished uppers in the pile, she almost invariably recounts them before tying them 30 up. In fact, the partly completed piles are often counted several times at different stages owing to interruptions in the work of the operator which cause her to forget how many uppers the piles contain.

One object of this invention is to relieve the operator of the necessity of counting the blanks which are being handled, thus avoiding 35 inaccuracy and insuring against interruption and delay in the progress of the work such as that resulting more or less frequently from necessary recounting of the blanks.

With this object in view, one feature of the invention consists in the provision of a 40 support constructed and arranged to sink as blanks are piled upon it one by one, an indicator, and means independent of the support and arranged to be actuated by the blanks as they are moved toward the pile for operating the indicator. In the illustrative ma-

chine the support is vertically movable and balanced so that it may gradually sink as the pile of blanks increases. This support is placed at the side of the vamper and has overhanging it an end of an actuator in the 55 form of a lever, downward movement of the overhanging end of which operates the indicator. With such a construction the vamper, by wiping each upper across the end of the lever as the upper is being placed upon the 60 pile, operates the indicator which will then show at any time just how many blanks the pile contains.

Uppers of shoes are bulky and do not lend themselves readily to the formation of a stable pile. According to another feature of the invention there is provided a presser which normally rests upon the top of the pile but is withdrawn when the actuator is moved. In the illustrative machine the presser is 70 connected with the actuator, both members being held in their normal positions by means of a weight. When the actuator is moved by engagement with a moving blank in the hand of the operator, the presser is withdrawn from the pile to permit the blank to be added to the pile. By this time the actuator has been released, and the presser is returned by the action of the weight to engagement with the top of the pile.

These and other features of the invention, including certain details of construction and combinations of parts, will be described as embodied in an illustrative machine and pointed out in the appended claims.

Referring now to the accompanying drawings—

Fig. 1 is a perspective of a machine in which the present invention is embodied;

Fig. 2 is a cross-section showing the actuator depressed and the presser withdrawn from the pile, and

Fig. 3 is a cross-section showing the actuator and the presser in their normal positions. In this figure a partly finished pile of 95 uppers is also shown.

The machine may conveniently be mounted upon a bench 5 at the side of the vamper, the bench being the same one upon which the sewing machine (not shown) of the 100

vamper is mounted. Fastened to the bench by screws 7 are two bars 8 having at their outer ends downwardly extending rods 9 the lower ends of which are connected by a bar 11. The rods 9 serve as guides for slidable sleeves 13 to which is fastened the table or support 15. This support is balanced by weights 17 suspended at the ends of cords 19 which are fast at their other ends to the support 15 and run over pulleys 21, the pulleys being sustained, as shown, by the bars 8. With this construction, the support will remain in any vertical position in which it may be placed and specifically will sink gradually as blanks are added to the pile and force exerted to move it downwardly.

Rotatably mounted upon a spindle 23 carried by a bracket 25 is an indicator 27 having fast to it a ratchet 29 which is adapted to be engaged and turned by a pawl 31. The pawl is pivoted to one end of a lever 33 which is pivoted at 35 to the bracket and at its other end at 37 to an actuator in the form of a lever 39. Pivoted at 41 to the lever 39 is a link 43, which extends down through a slot in the bench 5 and is pivoted at its lower end at 44 to one end of a link 45. This link is pivoted at 47 to an arm 49 and has suspended from that end of it which is remote from the pivot 44 a weight 51. The arm 49 is pivoted at 53 to a bracket, which is fast to the bench 5, and has fast to or integral with its upper end a presser in the form of a fork 55. A pin 57 guides the movement of the lever 39 when the outer end of the lever is depressed.

Normally the lever or actuator 39 and the presser 55 are in the positions shown in Figs. 1 and 3. It should be noted in this connection that in Fig. 1 the table or support 15 is shown in the same position as in Fig. 3, although the pile of blanks 100, which is shown in Fig. 3, is not shown in Fig. 1. Normally then, the presser is in engagement with the top of the pile of blanks or, if no pile is present, the presser is normally in position to engage a blank as soon as a blank is placed upon the support, while the actuator lies in the path of a blank which is being placed upon the support or added to the pile. In the operation of the machine the vamper, as soon as she has removed an upper from her sewing machine, wipes it down over the overhanging end of the lever 39 as she places the finished upper upon the support 15. This operation depresses the lever and withdraws the presser from the pile, as shown in Fig. 2; and then, as the upper slips off the end of the lever and is placed upon the top of the pile, the weight 51 returns the parts to their normal positions. The ratchet 29 and the pawl 31 are so proportioned and the

connections between the pawl and the lever 39 are such that for every depression of the lever the indicator is advanced one space. Consequently inspection of the indicator will apprise the operator at any time of the number of blanks in the pile so that she may tie them into a bundle when the desired number has been reached. To this end a cord 59 may conveniently be laid upon the support before the pile is started. 75 Preferably a cover is provided for the indicating wheel having the usual slot to expose one numeral at a time, and means are provided for resetting the indicator; but since such features are details of construction of the indicator and form no part of the present invention, they have not been shown.

In order to hold the parts firmly in their normal positions, as shown in Fig. 3, a catch 61, pivoted at 63 to the arm 49 is adapted to engage a pin 65 carried by a stationary bracket 67, said catch being pivotally connected with the link 45 by a link 69 and being limited in its downward movement about the pivot 63 by a projection 149 on the arm 49.

Although the invention has been set forth as embodied in a particular machine for use in handling uppers of boots and shoes and is adapted both to aid in piling the uppers and in counting them, it should be understood that the invention is not limited in its broader aspects to use with the particular blanks which have been shown nor to a machine which has both of these features.

Having thus described my invention, what I claim as new and desire to secure by Letters Patent of the United States is:

1. A machine for use in handling blanks, having in combination, a support constructed and arranged to descend as blanks are piled upon it one by one, an indicator, and means independent of the support and arranged to be actuated by each blank as it is placed upon the pile for operating the indicator to count the blanks.

2. A machine for use in handling blanks, having in combination, a movable balanced support upon which blanks may be piled, a movable member overhanging the support, an indicator, and means connected to the movable member and to the indicator for operating the indicator.

3. A machine for use in handling blanks, having in combination, a movable support upon which blanks may be piled, a presser, an actuator therefor, and means responsive to manipulation of the actuator for moving the presser.

4. A machine for use in handling blanks, having in combination, a support upon which blanks may be piled, said support being movable and balanced, a presser, an actuator therefor, and means responsive to

manipulation of the actuator for moving the presser.

5. A machine for use in handling blanks, having in combination, a support upon which blanks may be piled, a presser normally in position adjacent the support, an actuator therefor, means responsive to movement of the actuator for moving the presser away from the support, and means 10 operating when the actuator is released to return the actuator and the presser to their normal positions.

6. A machine for use in handling blanks, having in combination, a support upon which blanks may be piled, a presser capable of being withdrawn from and returned to engagement with the pile, and an actuator arranged to be engaged by a blank as it is being added to the pile for operating the presser to permit the addition of the blank and to hold it after it has been added.

7. A machine for use in handling blanks, having in combination, a movable support upon which blanks may be piled, a presser normally in engagement with the pile, an actuator, and means whereby movement of the actuator in one direction withdraws the presser from the pile and in the other direction returns the presser to engagement with the pile.

8. A machine for use in handling blanks, having in combination, a movable support upon which blanks may be piled, a presser normally in engagement with the pile, an actuator, and means whereby movement of the actuator in one direction withdraws the presser from the pile and release of the actuator permits return of the presser to engagement with the pile.

40 9. A machine for use in handling blanks, having in combination, a support on which blanks may be piled, a presser normally in position adjacent the support, an actuator therefor normally in a position more remote from the support than is the presser, and means responsive to movement of the actuator toward the support for moving the presser away from it.

50 10. A machine for use in handling blanks, having in combination, a support on which blanks may be piled, said support being movable and balanced so that the top of the pile may remain always approximately in the same plane as blanks are added to it, a presser normally in position adjacent the support, an actuator therefor normally in a position more remote from the support than is the presser, and means responsive to movement of the actuator toward the support for moving the presser away from it.

60 11. A machine for use in handling blanks, having in combination, a support upon which blanks may be piled, an actuator arranged normally in position to be engaged and moved by each blank as it is being

placed upon the support, means for returning the actuator to its normal position when its engagement with the blank ceases, a presser normally held in contact with the pile, and connecting means between the presser and the actuator constructed and arranged to withdraw the presser to permit each blank to be added to the pile, and then to return the presser to normal position.

70 12. A machine for use in handling blanks, having in combination, a vertically-movable, balanced support upon which blanks may be piled, a presser movable into and out of engagement with the pile, an indicator, and means pivotally connected to the presser 80 for operating the indicator.

13. A machine for use in handling blanks, having in combination, a support upon which blanks may be piled and counted, an actuator arranged to be engaged by each blank as it is being placed upon the support, a presser, and means responsive to movement of the actuator for moving the presser and counting the blanks.

90 14. A machine for use in handling blanks having, in combination, a balanced support constructed and arranged to descend as blanks are piled upon it one by one, an actuator adapted to be engaged and moved by each blank as it is being added to the pile, a presser adapted to engage the uppermost blank in the pile, connecting means between the presser and the actuator constructed and arranged to withdraw the presser when the actuator is moved by a blank to permit the blank to be added to the pile, a fixed stop operating through said connecting means to determine the normal position of the actuator and the presser, and a weight operating through said connecting means to return the actuator and the presser to their respective normal positions after each blank has been added to the pile.

100 15. A machine for use in handling blanks, having in combination, a support upon which blanks may be piled and counted, an actuator arranged normally in position to be engaged and moved by each blank as it is being added to the pile, means for returning the actuator to its normal position when its engagement with the blank ceases, a presser normally held in contact with the pile, and connecting means between the presser and the actuator constructed and arranged to withdraw the presser to permit each blank to be added to the pile and then to return the presser to normal position.

110 16. A machine for use in handling blanks, having in combination, a balanced support constructed and arranged to sink as blanks are piled upon it one by one, an actuator arranged normally in position to be engaged and moved by each blank as it is being added to the pile, means for returning the actuator to its normal position when its engage-

ment with the blank ceases, a presser normally held in contact with the pile, and connecting means between the presser and the actuator constructed and arranged to with-
5 draw the presser to permit each blank to be added to the pile and then to return the presser to normal position.

17. A machine for use in handling blanks, having, in combination, a support upon

which blanks may be piled, a presser nor-
10 mally in position to engage a blank placed upon the support, and means controlled by the movement of a blank which is being placed upon the support for moving the presser away from the support.

In testimony whereof I have signed my name to this specification.

LEWIS J. BAZZONI.
